UNITED STATES PATENT OFFICE.

WILLIAM H. AYER, OF CLAREMONT, NEW HAMPSHIRE.

PICKER-CHECK FOR LOOMS.

No. 872,780.

Specification of Letters Patent.

Patented Dec. 3, 1907.

Application filed April 27, 1906. Serial No. 313,988.

To all whom it may concern:

Be it known that I, WILLIAM H. AYER, a citizen of the United States, residing at Claremont, in the county of Sullivan and 5 State of New Hampshire, have invented certain new and useful Improvements in Picker-Checks for Looms, of which the following is a specification.

My invention relates to improvements in 10 picker-checks for looms, and refers particularly to an improved mechanism for stopping the flight of the shuttle as it is thrown from side to side in the looms now commonly in use for weaving textile fabrics.

15 The object of my invention is the provision of a device of this character which may be readily applied to the shuttle box guide of the ordinary looms now in use, and which will provide a yielding buffer to the picker 20 and will prevent rebounding of the shuttle.

Another object of the invention, is to provide a check which will yield quickly to the thrust of the picker and in the same plane as the picker, and will be provided with a contact surface not easily worn by continued 25 striking thereon.

Further objects of the invention are to provide a picker check which may be adjusted to suit different conditions, consisting 30 of but few and simple parts, and which will be thoroughly practical and efficient.

With these and other objects in view, my invention consists of a yielding impact band provided with a metal contact surface, a 35 fixed support and an adjustable eccentric support for the band, and a pair of springs connecting the ends of the band.

My invention also consists of a picker check embodying certain other novel features of construction, combination and arrangement of parts substantially as disclosed herein.

Figure 1, is a rear view of a portion of the shuttle box frame of an ordinary loom with 45 my improved shuttle check applied thereto. Fig. 2, is a vertical sectional view thereof on the line 2—2 of Fig. 1. Fig. 3, is a front elevation of my complete check. Fig. 4, is a rear end elevation of the same with a portion broken away to show the construction thereof, and Fig. 5, is a detached elevation of the base plate of the check.

Referring in detail to the drawings: The numeral 1, designates the shuttle box frame

of a loom, to which is attached the shuttle 55 box guide 2, by means of the bolts 3. The picker 4, picker-stick 5, and picker spindle or guide 6, are all of usual construction, as is also the shuttle box guide 2, provided with the guiding flanges 7. The foundation or 60 base plate to my improved check consists of a substantially triangular-shaped plate 8, which is shouldered as shown in dotted line in Fig. 3, so that it may be attached to the ordinary shuttle box guide by means of a 65 bolt or other suitable fastening 9. At the lower corner or apex of the plate and preferably formed integral therewith, is a lug or post 10, formed with an outer rounded wearing surface in the form of an arc as 70 shown. Near the upper portion of the plate, is formed a longitudinal slot 11, and passing through said slot is a bolt 12, provided on its end with a nut 13. Loosely mounted on said bolt and adapted to be fixedly secured 75 thereon by the said nut, is an eccentric roller 14, and passing over the roller and lug 10, is an impact band 15, preferably of leather. The pair of spiral springs 16, connect the 80 ends of the strap or band, and one of the springs may be anchored midlength, to the plate, by means of a fastening 17, so that the band will not slide out of position. As there is considerable friction on the strap at 85 its point of connection with the supporting posts, an extra layer may be secured on the inner side of the strap as at 18.

On the strap opposite the opening in the flanges, I provide a bearing for the picker to strike against which consists of one or more 90 layers of material 19, secured upon the strap by means of rivets or suitable fastenings 20, and the heads of the rivets thereby provide a durable contact surface and save wear of the strap. 95

From the foregoing, it will be seen that I have provided a double roll friction which allows the check strap to go straight back, and as the friction is thereby doubled, the shuttle will be prevented from rebounding 100 after having come in contact with the check. This is a very important feature as it prevents the shuttle rebounding, allowing the shuttle to be bound with less friction on the shuttle binder, and prevents the filling from 105 kinking and thus throwing off the bobbin.

From this description taken in connection with the drawings, the operation and advan-

tages of my improved shuttle check will be readily understood and appreciated.

The position of the impact strap with relation to the flanges of the shuttle box guide 5 may be altered by loosening the nut and changing the position of the eccentric roller, either by rotating, or moving the bolt in the slot.

I claim:

- 10 1. In a shuttle check, the combination with an impact band, shuttle guiding flanges, a fixed second support for the band, of a second support for the band adjustable both longitudinally of the band and laterally with respect to the guiding flanges.
- 15 2. In a shuttle check, the combination with an impact band, of a fixed support therefor having a rounded bearing surface, and an adjustable support capable of longitudinal and transverse adjustment with respect to the plane of the band.
- 20 3. The combination with an impact strap having an impact surface of harder material, of a pair of spiral springs connecting the ends 25 of the strap, means for anchoring the central portion of one of the springs, a fixed support for the band having a curved bearing surface,

and an adjustable support capable of longitudinal and transverse adjustment.

4. In a shuttle check, the combination 30 with an impact band, a fixed support for the band, of an adjustable eccentric support for the opposite end of the band.

5. A shuttle check comprising a fixed support, an eccentric support capable of rotary 35 and sliding adjustment, and an impact band arranged on said supports.

6. A shuttle check comprising a base plate, a fixed support thereon, an eccentric support mounted on the plate and capable of sliding 40 adjustment, and an impact band passing over said supports.

7. A shuttle check comprising a base plate, a fixed support thereon, a bolt secured in a slotted portion of the plate, an eccentric support 45 adjustably secured on said bolt, and an impact band arranged on said supports.

In testimony whereof I affix my signature in presence of two witnesses.

WILLIAM H. AYER.
